UNITED STATES PATENT OFFICE.

FOWLER MANNING, OF NEW HAVEN, CONNECTICUT, ASSIGNOR TO WINCHESTER REPEATING ARMS CO., OF NEW HAVEN, CONNECTICUT, A CORPORATION.

DESIGN FOR A SHOW CASE FOR SHOULDER-ARMS.

52,223.

Specification for Design.

Patented July 23, 1918.

Application filed March 23, 1918. Serial No. 224,350. Term of patent 14 years.

To all whom it may concern:

Be it known that I, FOWLER MANNING, a citizen of the United States, residing at New Haven, in the county of New Haven and State of Connecticut, have invented a new, original, and ornamental Design for a Show-Case for Shoulder-Arms, of which the following is a specification, reference being had to the accompanying drawing, forming part thereof.

The figure is a perspective view of a show-case for shoulder arms showing my new design.

I claim:

The ornamental design for a show-case for shoulder arms, as shown.

FOWLER MANNING.
